UNITED STATES PATENT OFFICE.

WILLIAM S. ELLIOTT, OF PITTSBURGH, PENNSYLVANIA.

TUBE-CLEANING TOOL.

1,032,193.

Specification of Letters Patent.

Patented July 9, 1912.

Application filed February 16, 1910. Serial No. 544,166.

To all whom it may concern:

Be it known that I, WILLIAM S. ELLIOTT, of Pittsburgh, Allegheny county, Pennsylvania, have invented a new and useful Tube-
5 Cleaning Tool, of which the following is a full, clear, and exact description, reference being had to the accompanying drawings, forming part of this specification, in which—

10 Figure 1 is a plan view partly broken away of a tube-cleaning tool embodying my invention; Fig. 2 is an end view of the same; Fig. 3 is a perspective view of the head and cap members shown in separated position; Figs. 4 and 5 are respectively plan and end views showing a modification of the invention; and Fig. 6 is a detail view.

In my application Serial No. 544,165 of even date herewith, I have shown and de-
20 scribed, and broadly claimed, a tube-clean-
ing tool having a plurality of freely swing-
ing tool-carrying arms, the pivots for said
arms being arranged obliquely to the lon-
gitudinal axis of the tool, and said arms be-
25 ing arranged to swing freely outward un-
der the centrifugal force of rotation to de-
liver a rapid succession of hammer-like
blows upon the scale or other material to
be removed from the pipes or tubes. Each
30 of the freely swinging arms is provided
with a cutter wheel having longitudinally
extending teeth or corrugations, this form
of wheel having been found to be very ef-
fective in service when used with a freely
35 swinging arm. In practice I have found
the oblique arrangement of the pivots for
the arms to be of great importance, for the
reason that by this arrangement, which
causes the arms to move in oblique lines, the
40 teeth of the cutting wheels, instead of be-
ing presented to the scale on the interior of
the tubes in lines parallel to the axis of the
tubes, are caused to attack the scale at a
angle, thereby preventing any tendency of
45 the cutters to "track", and making their
action much more effective. In the specific
form of tool shown and described in said
application, the freely swinging arms are
mounted to swing in planes which are in
50 general transverse to the longitudinal axis
of the tool, although somewhat oblique to
such axis.

In the form of tool herein shown and de-

scribed, the freely swinging arms are mounted to swing in planes which are in 55 general longitudinal, although somewhat oblique to the longitudinal axis of the tool as a whole, and the invention is designed to provide a tube-cleaning tool of this character which shall be simple in its construction, 60 effective in its operation, and in which the parts are so constructed and arranged as to enable repairs to be quickly and readily made.

A further object is to provide means of 65 novel character for retaining in place the pivot pins for the freely swinging arms and to obviate the use of rivets, bolts, or other fastenings of a kind difficult to remove or which might work out of place in use. 70

In the drawings, the numeral 2 designates the head of the tool, which is pro-
vided with a screw-threaded shank 3, or
other suitable means for its attachment to
the shaft of an actuating motor. The head 75 is formed with a plurality (in this case,
four) equally distant, oblique, slots 4, to re-
ceive the inner ends of the freely swinging
cutter carrying arms 5. The slots 4, as will
be clearly seen from the drawings, are ob- 80
lique to the longitudinal axis of the head, so
as to cause the freely swinging arms to vi-
brate in planes which are also oblique to
the axis of the head and of the pipe or tube
being cleaned. Each arm is secured in place 85
by, and vibrates on, a pivot pin 6, which is
inserted through an opening in the inner
end of the arm, and is seated in perfora- 90
tions 7 in the side walls of the slots 4, these
side walls being formed by lugs projecting
from the central portion of the head. The
pins are secured in place and held against
displacement by means of a cap member 8, 95
which is arranged to be slipped loosely over
the threaded shank 3, and has four triangu-
lar lugs or projections 9 which are shaped
to fit in the angles between the outer walls
of the slot-forming lugs of the head. The
cap is secured in place by means of a nut 10
10 on the threaded shank 3, or by any other
suitable means which will permit the cap
to be readily removed when necessary.

Each of the freely swinging arms is pro-
vided at its forward end with a longitudi-
nally tapered toothed cutter wheel 11, which 105
is preferably mounted so as to rotate freely.

These cutters are journaled on pins or shafts 12 extending longitudinally through the arms, with heads 12^a at their forward ends. They are held in place by the pivot pins 6, 5 which engage recesses 12^b therein.

In the form of my invention shown in Figs. 1 and 2, the slots 4 are so arranged as to bring the freely swinging arms into two converging pairs, as clearly seen in Fig. 2. 10 In the form shown in Figs. 4 and 5, the corresponding slots 4^a are so arranged as to cause each arm to diverge from the adjacent arms, so that their forward ends, together with the cutter wheels 11^a will be 15 equally spaced around the periphery of the head.

In operation, the head with the freely swinging arms is rapidly rotated within the pipe or tube to be cleaned; and the 20 centrifugal force of rotation causes the arms to exert a rapid succession of vibratory or hammer-like blows, the toothed cutter wheels thereby attacking the scale or other deposit to be removed in a highly effective 25 manner. The oblique disposition of the arms brings the teeth of the cutter wheels in lines oblique to the axis of the tube, thereby enabling them to exert a cross-cutting action, which effectively prevents tracking and 30 insures the removal of all adhering scale.

As shown in the drawings, I prefer to make the arms of different lengths. In the particular forms shown, two of the arms are shorter than the other two. They may, 35 however, all be made the same length, or each arm may be of a different length so as to cause the respective cutters to work in different circular paths. I do not limit myself to the use of any particular number of 40 arms; and if desired, each arm may be provided with a plurality of cutters instead of a single cutter. By means of the cap member 8, the pivots for the arms are enabled to be loosely slipped into place, and then 45 held against displacement, thereby obviating the use of rivets or bolts, and enabling any pivot to be quickly reached in case of breakage or injury to one or more of the arms. I do not, however, limit myself to 50 the exact construction and arrangement of the pivot retaining or cap member which I have herein shown and described, since ob-

viously this will vary with the number and exact arrangement of the arms.

What I claim is:—

1. A tube cleaner comprising a rotatable head having a plurality of recesses therein, cutter carrier arms pivoted in said recesses, pivot pins for said arms having bearings in the walls of said recesses, and a single 60 keeper for all of the pivot pins, said keepers having portions which engage the ends of said pins; substantially as described.

2. A tube cleaner comprising a rotatable head having a plurality of recesses therein, 65 said recesses being open at both ends, cutter carrier arms pivoted in said recesses, pivot pins for said arms having bearings in the walls of said recesses, and a single 70 keeper for all of the pivot pins, said keeper having portions which engage the ends of said pins; substantially as described.

3. A tube cleaner comprising a rotatable head having a plurality of slots therein open at both ends, a plurality of cutter 75 carrying arms pivoted in said recesses and having pivot pins seated in bearings in the walls of said recesses, said head having angular recesses intermediate of said slots, and a keeper member having a plurality of 80 projections arranged to fit said recesses and engage the ends of the pins; substantially as described.

4. A tube cleaner comprising a rotatable head having a projecting shank formed with 85 a plurality of open end slots, a plurality of cutter-carrying arms pivoted in said slots and having their pivot pins provided with bearings in the walls of the slots, the head having angular recesses intermediate the 90 slots, a keeper arranged to fit over the threaded shank and having a plurality of projections fitting the said recesses and engaging the ends of the pins, together with means for normally securing the keeper 95 against longitudinal movement; substantially as described.

In testimony whereof, I have hereunto set my hand.

WILLIAM S. ELLIOTT.
